US00D806177S

(12) **United States Design Patent** (10) **Patent No.:** **US D806,177 S**
Liu et al. (45) **Date of Patent:** **** Dec. 26, 2017**

(54) **FOOT-CONTROL STEERING LEVER FOR SCOOTERS**

(71) Applicant: **NINEBOT(BEIJING)TECH. CO., LTD**, Beijing (CN)

(72) Inventors: **Lei Liu**, Beijing (CN); **Hui Zhang**, Beijing (CN); **Xudong Jiang**, Beijing (CN)

(73) Assignee: **Ninebot (Beijing) Tech. Co., Ltd.**, Beijing (CN)

(**) Term: **15 Years**

(21) Appl. No.: **35/500,947**

(22) Filed: **Feb. 1, 2016**

(80) **Hague Agreement Data**

Int. Filing Date: **Feb. 1, 2016**

Int. Reg. No.: **DM/090411**

Int. Reg. Date: **Feb. 1, 2016**

Int. Reg. Pub. Date: **May 13, 2016**

(30) **Foreign Application Priority Data**

Aug. 21, 2015 (CN) 2015 3 0316181

(51) **LOC (10) Cl.** **21-01**

(52) **U.S. Cl.**

USPC **D21/423**

(58) **Field of Classification Search**

USPC D6/354, 355; D21/423

CPC B62J 1/002; B62J 1/005

(57) **CLAIM**

The ornamental design for a foot-control steering lever for scooters, as shown and described.

DESCRIPTION

Figure 1.1 is a front view of a foot-control steering lever for scooters showing our new design;

Figure 1.2 is a back view thereof;

Figure 1.3 is a left view thereof;

Figure 1.4 is a right view thereof;

Figure 1.5 is a top view thereof; and

Figure 1.6 is a bottom view thereof.

The broken line showing of the connecting elements is included for the purpose of illustrating portions of the "article" and forms no part of the claimed design.

1 Claim, 6 Drawing Sheets
